3 Claims. (Cl. 107—17)

The present invention relates to an improved apparatus for producing single- and/or multi-layer tablets.

Tablet making machines are known having a rotary turret and wherein the matrices or moulds pass beneath a filling device which consists of a filling shoe or box to which the material being handled is continuously supplied by gravity from a funnel. The material being handled passes from the fixedly mounted filling shoe into the matrices of a horizontal rotating matrix wheel and is then compacted by means of plungers to form tablets. The rotary speed of the matrix wheel and thus the number of articles which can be produced in a given time is obviously limited because if the speed is too high the matrices are only incompletely filled with material so that the tablets produced are of low and uncertain weight.

It is an object of the present invention to overcome this disadvantage by filling the matrices intermittently and compacting the material only at those times when the material is being moved past the matrices.

The invention is based on recognition of the fact that with the known filling devices the relative speed between the material to be compacted and the matrix wheel is the same as the speed of the matrix wheel. Since a definite relative speed, varying according to the nature of the material being handled, should not be exceeded for satisfactory filling of the matrices, the present invention provides that the material to be compacted shall be moved in the same direction whereby a further increase in the matrix speed is possible, without the relative speed falling outside of the limits within which exact filling is possible.

This is permitted according to the invention by arranging the filling device as a ring-shaped filling frame which extends concentrically around the whole matrix wheel in the region of the matrices. As a result of the construction of the device in the form of a ring-shaped frame the material to be compacted and supplied to the matrix wheel is no longer held stationary at one point, as when using a rigidly mounted filling shoe, but participates in the movement of the matrix wheel although at a lower speed, the difference providing the relative speed which enables the matrices to be filled. The material being handled is swept towards and away from the matrices by means of suitably placed guide blades attached to the filling device, the matrices passing beneath these guide blades which thus also serve to strike off the material collecting in the matrices. By means of this deflection or striking off and by windage effects the press material is slightly retarded as regards its speed derived from the matrix wheel so that it moves with a small relative speed over the matrix wheel. Thereby the matrices are always sufficiently filled even at high rotary speeds of the matrix wheel.

The material to be filled into the matrices is supplied by one or more supply funnels provided at certain points of the frame-like filling devices and is constantly made up as required.

If several materials must be handled for the production of multiple-layer or coated tablets, which consist of powder, granular material or pre-compactated tablet cores, this can be obtained in a simple manner by providing additionally two or more ring zones for the various materials,

2

which zones are associated with corresponding sweeper blades or deflectors.

The main constructional parts of one example of the invention are illustrated diagrammatically in the accompanying drawing, wherein:

FIG. 1 is a plan view showing a rotary table carrying matrices or moulds with a stationary filling frame above it for a filling device supplied with two different pressing materials, and

FIG. 2 is a section on the line A—B of FIG. 1.

Referring to the drawing, ring-shaped filling zones are formed above the surface of a rotary wheel 2 provided with a concentric series of matrices 1 and driven in the horizontal plane in the direction of the arrow P, these filling zones being formed by exchangeable stationary ring-shaped walls 3, 4 and 5 substantially in contact with the upper face of the wheel 2 and provided with obliquely placed deflector blades 6 and segmental guide walls 7 which latter are concentric with the circular walls 3, 4 and 5. The blades 6 sweep the tablet forming materials between the walls 3, 4 and 5 towards and away from the matrices 1 and cause such material to rotate with the wheel 2 but at a slightly lower speed.

In the disclosed constructional example the production of multiple-layer tablets is intended and a first material G to be compacted and a second material G₁ to be compacted is supplied to the wheel 3. These materials which may be, for example, in the form of powders are supplied separately from supply funnels, not shown, into filling zones defined by the walls 3, 4 and 5 and wall segments 7, over the sector S indicated on the drawing.

A part of the material G is swept towards the matrices 1 by one of the blades 6 directed outwardly of the wall 5, while the material G₁ is initially merely carried onward by the rotating matrix wheel 2. The central wall 4 has inwardly and outwardly directed blades 6, the first of which sweeps the material G away from the matrices and in the following sector S₁ it is held away by means of a segmental wall 7. The material remaining in the matrices 1 is then pre-compactated in this sector region by means of a plunger, not shown.

The material G₁ carried with the matrix wheel 2 now runs against a first sweeper blade 6 on the outer wall 3 whereby it passes into the region of the matrices over the sector S₂. A portion of the material G₁ is placed upon the pre-pressed material G in the matrices 1, while the excess amount of material G₁ is pushed away by means of a following outwardly directed sweeper blade or deflector 6 on the wall 7. In the following sector S₃ a further compacting takes place.

On the further rotary movement of the matrix wheel 2 the material G₁ is swept by reason of the blade 6 towards the matrices over the region of a sector S₄ whereby again a partial amount of this material flows into the matrices 1. In the following sector S₅ there is a further compacting.

The material G carried with the matrix wheel from the region of the sector S₁ up to the end of the sector S₅ now passes into the region of the sector S₆ and thus again and finally comes towards the already nearly finished tablets T (FIG. 2) in the matrices 1.

The excess amount of material G is then deflected again by the blades 6 or deflector walls 7 and passes through the final sectors S₇ and S₈ and thence to the first sector S.

The excess amount of material G₁ passes from the end of the sector S₅ over the sectors S₆ and S₇ and S₈ again in the same way to the first sector S.

The final compacting occurs in the sector S₇, and in the sector S₈ finished multiple-layer tablets T are lifted out of the matrices 1 above the level of the wheel 2 by a bottom plunger 8 (FIG. 2), as far as the level

of a guide plate 9 and they are then swept onto the guide plate 9 by an oblique extension of the guide wall 7 between sector S₈ and sector S.

It will be understood that instead of compacting several powdered materials on the wheel, it would for example also be possible to employ previously compacted tablet cores which are pressed together with layers of a powdered material, thus forming additional layers of the tablet.

What I claim is:

1. An apparatus for producing tablets comprising a rotary table provided with a concentric series of tablet-forming matrices, means for supplying two tablet-forming materials to the surface of said table, comprising inner and outer annular guide walls to define annular surfaces adapted to receive said two tablet-forming materials, inwardly directed sweeper blades on the outer wall to sweep a first tablet-forming material towards the matrices, outwardly directed sweeper blades on the inner wall to sweep a second tablet-forming material towards the matrices, an intermediate guide wall disposed between said inner and outer guide walls and having sweeper blades directed inwardly and outwardly alternately to cause said tablet-forming materials to successively clear said matrices, short segmental guide walls forming an extension to selected sweeper blades to define a segmental portion where no tablet-forming material can pass towards the matrices, means to compact the material in said matrices over said segmental portions, and a guide plate lying at a level above the table surface for removal of completed tablets in a path lying over the second tablet-forming material.

2. An apparatus for producing tablets, comprising a rotary table provided with a concentric series of tablet-forming matrices, means for supplying a tablet-forming material to the surface of said table, circular guide walls arranged above said rotary table to define ring-shaped zones adjoining the path of said matrices, and a device for compacting the material into the matrices and com-

prising plungers arranged in a circular path, said ring-shaped zones being concentric to the matrices and having blades at several points serving as deflectors, means for guiding the materials to be compacted at these points out of the region of the matrices, then past such matrices, then again into the region of such matrices, to effect a filling of the same, and means whereby at those points at which the material is moved away from the matrices the material already in the matrices is compressed, the tablet-forming material being carried around on the surface of the table at a speed less than the speed of the table.

3. An apparatus for producing tablets, comprising a rotary table provided with a concentric series of tablet-forming matrices, means for supplying a tablet-forming material to the surface of said table, circular guide walls arranged above said rotary table to define ring-shaped zones adjoining the path of said matrices, and a device for compacting the material into the matrices and comprising plungers arranged in a circular path, said ring-shaped zones being concentric to the matrices and having blades at several points serving as deflectors, means for guiding the materials to be compacted at these points out of the region of the matrices, then past such matrices, then again into the region of such matrices, to effect a filling of the same, and means whereby at those points at which the material is moved away from the matrices the material already in the matrices is compressed, said ring zones being formed by interchangeable circular walls, the tablet-forming material being carried around on the surface of the table at a speed less than the speed of the table.
